(57) **CLAIM**

The ornamental design for a needle safety device, as shown and described.

DESCRIPTION

FIG. 1 is a front perspective view of a needle safety device in accordance with the present invention;

FIG. 2 is a rear perspective view thereof;

FIG. 3 is a right side view thereof;

FIG. 4 is a left side view thereof;

FIG. 5 is a top view thereof; and,

FIG. 6 is a bottom view thereof.
